UNITED STATES PATENT OFFICE

ROBERT C. LEGAT, OF NEW BRITAIN, CONNECTICUT, ASSIGNOR TO G. E. PRENTICE MANUFACTURING COMPANY, OF NEW BRITAIN, CONNECTICUT, A CORPORATION OF CONNECTICUT

SLIDER

Application filed January 6, 1932. Serial No. 584,995.

This invention pertains to separable fasteners of the slider operated type, such for example as described in the patent to Prentice, No. 1,658,392, February 7, 1928, and relates more particularly to an improved actuating slider for such fasteners. The field of usefulness of fasteners of this general class has been extended to include undergarments, for example corsets, but for such use the entire fastener, including the actuating slider, must be made of as small dimensions, particularly in a front to rear direction, as is practical, for unless the fastener device be very flat and thin it may cause unsightly bulges in the outer garments, as well as real discomfort to the wearer. Usually the fastener actuating slider is provided with a pull or operating tab, commonly consisting of a piece of metal adapted to be seized between the thumb and finger for use in moving the slider, and ordinarily this pull tab is attached to the slider proper by means such as a rivet, lug, or loop, which projects out from the plane of the front wing of the slider, thus adding very materially to the bulkiness of the slider in the front to rear direction.

The principal object of the present invention is to avoid the above difficulty and to provide an acceptable slider for the suggested purpose, which is of minimum front to rear thickness, although provided with suitable operating means useful in positively pulling the slider in either direction along the series of fastener elements. In accordance with this invention I attain the desired object in a very simple way, and without necessitating substantial alteration in or departure from usual slider construction in so far as the slider body proper is concerned, and without adding substantially to the cost or complexity of the process of manufacture.

In the accompanying drawing wherein I have illustrated one specific embodiment of the invention by way of example,

Fig. 1 is a fragmentary front elevation to large scale of a fastener device of the type referred to, showing the actuating slider as spaced from one end of the fastener and embodying the present invention;

Fig. 2 is a plan view to large scale of a

blank useful in forming my improved slider; Fig. 3 is a view of the blank of Fig. 2 after the first step in the shaping operation;

Figs. 4 and 5 represent further steps in the shaping operation;

Fig. 6 is an edge elevation of the slider complete, except for the pull members;

Fig. 7 is a section on the line 7—7 of Fig. 6; and

Fig. 8 is a perspective view illustrating one of the pull attaching elements to large scale and detached from the slider proper.

Referring to the drawing, the numerals 1 and 2 indicate flexible stringers of the usual type employed in such fasteners, the respective stringers carrying the series of fastener elements 3 and 4 which may be of any usual type. The opposed series of fastener elements are moved into and out of engaging relation by means of the slider 5 in a manner which is common and well known in the art.

Referring to Fig. 2, I prefer to make my improved slider from a single piece of sheet material which is cut, punched, or otherwise prepared, in accordance with known processes, the completed blank comprising the front and rear wing portions 6 and 7, respectively, united by the neck portion 8. At the free end of one of the wings, for example the end of the wing 6, I provide a pull attaching member consisting of a loop 9 preferably integral with the material of the wing and cooperating with the latter to form an opening or eye 10. While as stated the loop member 9 is preferably formed integral with the wing, it is obvious that it might be made of a separate piece, soldered, welded, or otherwise secured in position.

After the preparation of the blank, the next step usually consists, as indicated in Fig. 3, in turning up the lateral margins of the wings to form the flange members 11 and 12, respectively. Following this flanging operation, the blank is bent at the neck portion so as to bring the wings into substantially parallel spaced relation, with the flanged edges of the wings directed inwardly. This bending operation may be accompanied or followed by the step of depressing the neck portion transversely, as indicated at 13 in

Fig. 4. Following this step, the neck portion is successively further depressed, while at the same time the transverse width of the slider is decreased by appropriately applied pressure, so that, as shown in Fig. 5, a deep trough-like recess 14 is formed at the neck portion of the slider extending from front to rear, all as more fully described in the co-pending application of George E. Prentice, Serial No. 562,518, filed September 12, 1931.

Preliminary to the next step in the operation, I prepare a second pull attaching member, such as shown for example in Fig. 8. Such attaching member may, for example, be made by punching the desired shape from sheet material, although the exact mode of preparation of this part is immaterial, and in its preferred form is of substantially A-shape, comprising the upper or loop portion 15 and the transverse crossbar 17 which cooperate to define the opening or eye 16. Below the crossbar 17 the side members of this A-shape structure extend downwardly in the form of legs 18 and 19.

Having prepared the attaching member as just described, the crossbar 17 of such attaching member is now placed in the recess 14 of the partially completed slider, and the corner portions 20 and 21 of the latter are then caused to approach while continuing the lateral inward pressure upon the slider body, so that eventually the parts take the position indicated in Fig. 7 where the crossbar 17 is wholly confined or embedded within a recess 35 or opening 14 extending from front to rear through the tubular neck of the slider. During the operations of forming the slider body, substantially V-shaped recesses 22 are produced in the front and rear wings at 40 the neck, and these recesses receive the downwardly projecting leg portions 18 and 19 of the second pull attaching member. These legs thus seated in the V-shaped recess substantially prevent the loop member 15 from swinging about the crossbar 45 17 as an axis, so that the pull attaching member is rigidly held in position. At any suitable stage of the process the loop member 9 may, if desired, be deflected forwardly to a slight extent, as shown at 9^a in Fig. 6, to accommodate the thickness of the pull between the loop and the forward faces of the fastener elements. For convenient actuation of the slider thus prepared, I preferably attach 50 to the loop 15 a flexible pull member 23 consisting, for example, of a piece of ribbon, tape, or the like, and likewise attach a similar pull member 24 to the loop member 9. These pull members 23 and 24 may be of a similar material and/or color to that of the garment to which the fastener is to be applied, and being soft and flexible will not cause discomfort to the wearer. At the same time it may be noted that the pull attaching 55 member 15 is disposed within the plane of

the body of the slider, as shown in Fig. 6, while the attaching member 9 may lie in such plane or very slightly deflected therefrom, as shown in Fig. 6. Thus, there is no substantial projection beyond the plane of the front wing, such as unduly to increase the front and rear thickness of the slider, so that the fastener is well adapted for use on undergarments, where it does not occupy an undue amount of space and does not produce bulges in the outer garments or subject the wearer to discomfort or danger of injury. At the same time, means is provided for positively pulling the slider in either direction along the series of fastener elements, so that the slider is adapted for use with fasteners which are not designed to be opened by a tearing apart action, or whenever it is desired to move the slider positively in opposite directions by means of directly applied force.

While I have disclosed a certain desirable embodiment of the invention, I wish it to be understood that the invention is not necessarily limited to this particular embodiment but that changes in shape, proportion and size of parts may be made as well as substitution of equivalents without departing from the spirit of the invention. Likewise it is to be understood that while the invention has been shown in association with a slider made according to a certain described method, the invention is of broader utility and may be applied to sliders of other specific construction.

I claim:

1. A slider for fasteners of the class described, said slider having front and rear wings united at one end by a neck, a loop member secured to the neck portion of the slider and disposed within the plane of the slider body, a loop member integrally united to the lower end of one of the wings and projecting downwardly therefrom, and flexible pull members secured to the respective loop members.

2. A slider for fasteners of the class described, said slider having front and rear wings united at one end by a neck, said neck having a recess therein, a loop member having anchoring means disposed in said recess in the neck of the slider, a pull secured to said loop member, and a second pull attached to the slider at a point remote from the neck.

3. A slider for fasteners of the class described, said slider having front and rear wings united at one end by a neck, said neck having an opening extending therethrough from front to rear, a pull attaching member of A-shape having a cross-bar embedded in the neck, the front and rear wings of the slider having recesses adjacent to the neck, and the attaching member having legs disposed in the respective recesses.

4. A slider for fasteners of the class de-

scribed, said slider having front and rear wings united at one end by a neck and having a loop member integral with the lower end of one of the wings and projecting downwardly therefrom, a pull device attached to said loop member, and pull attaching means adjacent to the neck of the slider and disposed in the plane of the slider body.

5. A slider for fasteners of the class described, said slider having front and rear wings united at one end by a neck and having a pull attaching element rigidly secured to the neck portion of the slider and disposed within the plane of the slider body, a flexible pull directly secured to said attaching element, a second attaching element secured to the lower end of the front wing and extending downwardly therefrom, and a flexible pull directly secured to said latter attaching element.

10 20 Signed by me at Berlin, Connecticut, this fourth day of January, 1932.

ROBERT C. LEGAT.
